UNITED STATES PATENT OFFICE.

EDWIN S. MATTHEWS, OF NEW YORK, N. Y., ASSIGNOR, BY MESNE ASSIGNMENTS, TO HOWARD H. WILLIAMS AND ALBERT C. WALL, RECEIVERS OF THE STANDARD PLUNGER ELEVATOR COMPANY.

SPEED-REGULATOR FOR ELEVATORS.

1,212,154.

Specification of Letters Patent.

Patented Jan. 9, 1917.

Application filed November 3, 1905, Serial No. 285,703. Renewed April 7, 1914. Serial No. 830,290.

To all whom it may concern.

Be it known that I, EDWIN S. MATTHEWS, a citizen of the United States, residing at New York city, in the county of New York and State of New York, have invented certain new and useful Improvements in Speed-Regulators for Elevators, of which the following is a full, clear, and exact specification.

10 This invention relates to speed regulators for hydraulic elevators, and has special reference to improvements whereby the speed of an elevator may be automatically controlled through variations in pressure, without causing a sudden stoppage of the car and excessive strain upon the apparatus.

15 A considerable difference of pressure usually exists between the interior of the cylinder and the connecting pipe, particularly when the car is moving at a high speed, and the object of my invention is to utilize this differential pressure to actuate mechanism which will vary the cylinder port area, and thereby regulate the speed of the car.

20 25 A further object of the invention is to utilize the velocity of the flow itself to produce an additional or resultant pressure which is applied to regulate the speed. By my invention, the regulation takes place within the main cylinder, and preferably at the main cylinder port, in order to secure a greater effectiveness and better regulation than where the regulating devices are disposed at a distance therefrom. By locating 30 35 the valve in the main cylinder adjacent the port, quicker action is secured and excessive strains on the piping and connections outside the cylinder avoided.

According to my invention, I have provided a gate or valve at the main cylinder port, actuated by a piston contained in an auxiliary cylinder, and connected on one side with the interior of the main cylinder, and on the other side with the connecting 40 45 50 pipe, so that the position of the auxiliary piston, and consequently of the regulating gate, depends upon the difference between the pressures on the opposite sides of the piston. Means are also provided to cause the flow to create a partial vacuum on one or the other side of the piston and thereby increase the effect of the pressure on the other side.

The invention will be more fully described in connection with the accompanying drawing, wherein—

55 Figure 1 represents a vertical section of an elevator cylinder having my improvements applied thereto, Fig. 2 is a horizontal section. Fig. 3 is a detail view. Fig. 4 is a detail view of the adjusting valve. Fig. 5 is an enlarged detail, showing the flared end of one of the pipe connections.

1 represents an elevator cylinder having a flange 2 threaded thereon. Bolted to the flange 2 is the cylinder head 3, having the 60 passage 4 and the ported ring 5, forming the main port and communicating with the interior of the cylinder.

70 75 80 Figure 2 is a horizontal section of the cylinder 1, showing the gland 7 through which the plunger 8 passes, and containing the packings 9, held down by the end cap 10. Movable mounted on the ring 5 is a ported ring 11 having ports corresponding with those of the ring 5. The ring 11 has a pin 12 which is engaged by a forked lever 13, mounted on a shaft 15, which latter is rocked by a lever 16, thereby oscillating the ring 11 and opening or closing the ports of the ring 5.

I will now describe the means by which 85 the difference of pressure is caused to move the ring 11 in one direction or the other to open or close the main cylinder port, and thereby control the speed of the car.

85 90 95 Figure 3 is a detail view of the auxiliary cylinder 17, having a piston 18 mounted on a rod 19, which is connected to lever 16. The movement of the piston in both directions is cushioned and retarded by a dash-pot arrangement, consisting of a rod 20 fitting loosely in a small cylinder 21. Leading from the cylinder 1, to the cylinder 17 is a pipe 22, which preferably flares away from the main port, as shown. From the pipe 4, a pipe 23, also flaring away from the main port, leads to the opposite side of piston 18.

100 105 110 Figure 4 is a divided by-pass pipe, having spring seated pop valves 25, 26, opening one away from, and the other toward, the main cylinder for allowing excess pressure to escape around the auxiliary cylinder after moving the piston 18. The pipe 23 has a short pipe 27 leading therefrom and containing a cock 28, which is normally closed when the cock

29 is open but when open permits the cylinder pressure through pipe 22 to actuate the piston 18, for the purpose of testing the operation. A weight 30 sliding in guides 32 and raised by two armed lever 31 or suitable springs, may be provided to keep the movable ring 11 centered, as seen in Fig. 2, so that the main port will be normally open.

5 The operation of the apparatus depends upon the difference between the pressures in the pipes 22, 23, causing a resultant movement of the ring 11 to throttle the main cylinder port and retard the speed of the car. Assuming that the water flows into the main cylinder through the pipe 4, to cause the car to go up at a normal speed, no movement of the piston 18 and consequent throttling of the main port will occur, because of the centering weight, or whatever other device may 15 be used, though there will necessarily be some slight difference of pressure on the opposite sides of the piston 18. As soon as the car acquires an abnormal speed going up, for instance, the supply pressure will rise 20 relatively to the cylinder pressure, and the piston 18 will be moved downward in Fig. 2, moving the ring 11 and partially closing the main ports. When the car is going down at 25 too high a speed, the piston 18 will be moved oppositely in a similar manner.

It will be observed that the pipes 22 and 30 have flaring ends projecting away from the main ports, the object being to accentuate the effect of the difference in pressure, 35 by causing one to direct the flow toward the piston 18, the other at the same time acting to create a partial vacuum and consequently reducing the pressure on that side. Thus, if the car be ascending, the 40 pressure will be through pipe 23 to the piston 18, and at the same time, the flow will be downward from the main ports past the flared end of pipe 22, tending to reduce the pressure in pipe 22 by producing a partial 45 vacuum, thus accentuating the difference in pressure. An advantage in locating the valve at the cylinder head is that the back pressure due to the necessary change in direction of the water when it enters or leaves 50 the cylinder helps to balance the valve, rendering it easily operated by variations in pressure, or other means. So far as I am aware, it has not been heretofore proposed to cause the flow to simultaneously vary the 55 pressure on both sides of a pressure regulator, and thereby actuate a valve. This construction enables movable devices in the connecting pipe for restricting the flow to be dispensed with and the actuating connections for the valve to be disposed where 60 most desirable. It will therefore be understood that my invention is not to be restricted to any particular actuating means, or construction of pressure controlled devices, though it is preferable to have the

pressure connections disposed at opposite sides of the main cylinder ports, rather than on the same side.

In order to test the operation of my apparatus, I close cock 29, and open cock 28 thus entirely removing pressure from one side of piston 18, so that the cylinder pressure through pipe 22 can throttle the main ports. The pipe 22 may also have similar devices for testing the operation in the opposite direction. To prevent abnormal increases from actuating the piston suddenly, the divided by-pass 24, is provided, and the loaded valves 25, 26 are oppositely set so as to open upon a marked increase of pressure, thereby preventing too sudden movement of the piston 18. I have thus provided a valve located within the main cylinder, which will control the speed of the car, in either direction, and which will not too suddenly check the car upon sudden increase in pressure. The by passes can also be independently adjusted so that the actuating pressures can be varied according to the direction of the car.

Modifications and changes may be made without departing from the scope of the invention, and I do not restrict myself to the precise construction I have shown and described.

Having thus described my invention, I declare that what I claim as new and desire to secure by Letters Patent, is,—

1. In a hydraulic elevator, the combination with a car and its plunger, of a receiving cylinder for said plunger, a perforated lining in a portion of said cylinder, and a movable device for throttling said perforations to regulate the outflow of motor fluid from said cylinder.

2. In a hydraulic elevator, the combination with a car and its plunger, of a cylinder for said plunger, a change valve connected to said cylinder, a lining for a portion of said cylinder and provided with a plurality of perforations to establish communication between said cylinder and change valve, and a movable throttle for closing one or more of said perforations to throttle the outflow of motor fluid from said cylinder to limit the speed of descent of the car.

3. The combination with a main cylinder, of an auxiliary cylinder containing a piston, connections between one side of the piston and the supply pipe of said main cylinder and between the other side of said piston and the interior of the main cylinder, and a valve in said main cylinder controlled by the movement of said piston for regulating the port area of said main cylinder, substantially as described.

4. The combination with a main cylinder, of an auxiliary cylinder containing a piston, connections between one side of the piston

and the supply pipe of said main cylinder and between the other side of said piston and the interior of the main cylinder, and a valve at the main cylinder port controlled by the movement of said piston for regulating the port area of said main cylinder, substantially as described.

5. The combination with a main cylinder, of a regulator within the cylinder, pressure operated means for actuating said regulator to vary the flow, and means comprising an adjustable valve whereby sudden action of said regulator due to excessive pressure is prevented, substantially as described.

10 15 6. The combination with a main cylinder, of an auxiliary cylinder containing a piston, a pressure connection from one side of said piston to the supply pipe of said main cylinder at a distance from the port, a pres-

sure connection from the other side of said piston to the interior of said main cylinder at a distance from the port, and a valve within the main cylinder mechanically connected with said piston and adapted to restrict the main port opening, substantially as described.

7. The combination with a main cylinder, of a speed regulating valve located therein, and actuating connections for said valve controlled by variations in pressure to or from said cylinder, substantially as described.

In testimony whereof I affix my signature, in presence of two witnesses.

EDWIN S. MATTHEWS.
